UNITED STATES PATENT OFFICE.

RICHARD SYLVESTER, OF LINDSAY, ONTARIO, CANADA.

THRESHING-MACHINE.

No. 863,466.

Specification of Letters Patent.

Patented Aug. 13, 1907.

Application filed January 26, 1906 Serial No. 298,039. Renewed May 2, 1907. Serial No. 371,473.

To all whom it may concern:

Be it known that I, RICHARD SYLVESTER, of Lindsay, in the county of Victoria and Province of Ontario, Canada, have invented certain new and useful Improvements in Threshing-Machines; and I hereby declare that the following is a full, clear, and exact description of the same.

In my application for Letters Patent of the United States, Serial Number 228,466, which has now matured into Patent 844,627, dated February 19, 1907, filed October 14th, 1904, I have shown and described a motor driven threshing machine in which the motor and radiator are suspended in front of the blower to heat the air as it enters therein, so that the air current forced by the fan through the separating mechanism will dry the grain as it passes through the separating mechanism. In this construction the heating of the air current is dependent upon the absorption of the heat units from the motor and radiator by the surrounding atmosphere, and the full calorific value of the heat units cannot be utilized as a greater or less percentage of them pass into and are absorbed by the atmosphere beyond the path or course of the air current entering the blower. I have found that by inclosing the blower casing or part thereof with a water jacket and connecting the water space of the water jacket with the water space of the motor by circulating pipes the full calorific value of the heat units generated by the motor may be employed to heat the air current within the blower as the fan revolves, as hereinafter more fully set forth and more particularly pointed out in the claims.

For a full understanding of the invention reference is to be had to the following description and to the accompanying drawings in which,

Figure 1 is a side elevation of a portion of the frame of a threshing machine showing the location of the motor and the water jacketed blower. Fig. 2 is a transverse section of the blower, water jacket and

motor. Fig. 3 is a longitudinal section of the parts shown in Fig. 2.

40

Like letters of reference refer to like parts throughout the specification and drawings.

As this invention relates to an improvement of the construction shown in the above patent, only those parts of said construction directly affected by the present invention will be shown and described.

Revolute within the blower casing *a* is the fan *a'* which creates the air current through the usual grain separating mechanism inclosed within the frame *a''*. The lower portion of the blower casing *a* is inclosed by a water jacket *b* connected with the water space of the motor *c* by circulating pipes *d* *d'* so that the water will flow from the water space of the motor to the water jacket of the blower and then return to the water space of the motor. Formed through the blower casing and water jacket is an air inlet *b'* to which is opposed the motor *c*. The water during its occupation of the water space of the motor absorbs the heat units from the motive agent of the motor and then circulates from the water space through the pipe *d* to the water jacket where the heat units of the water are transmitted to and absorbed by the air current created in the blower by the revolution of the fan. The absorption of the heat units by the air currents cools the water before it returns to the water space of the motor, and the heating of the air current dries the grain during its separation from the straw and its passage from the separating mechanism.

Having thus fully described my invention that I claim as new and desire to secure by Letters Patent is;

A grain separating mechanism having an air blower therefor, a water jacket around the blower, in connection with a motor having a water jacket and circulating pipes connecting the water jackets of the motor and air blower.

Toronto, December 21st, A. D. 1905.

RICHARD SYLVESTER.
